US00D878347S

(12) **United States Design Patent** (10) **Patent No.:** **US D878,347 S**
Ahn (45) **Date of Patent:** **** Mar. 17, 2020**

(54) **CASE FOR ELECTRONIC COMMUNICATIONS DEVICE**

(71) Applicant: **SPIGEN KOREA CO., LTD.**, Seoul (KR)
(72) Inventor: **Deok Hyun Ahn**, Seoul (KR)
(73) Assignee: **Spigen Korea CO., LTD.**, Seoul (KR)

(**) Term: **15 Years**

(21) Appl. No.: **29/621,238**

(22) Filed: **Oct. 5, 2017**

Related U.S. Application Data

(63) Continuation of application No. 29/598,701, filed on Mar. 28, 2017, now Pat. No. Des. 820,821.

(57) **CLAIM**

The ornamental design for a case for electronic communications device, as shown and described.

DESCRIPTION

FIG. 1 is a front perspective view of a case for electronic communications device showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof; and,
FIG. 8 is a bottom plan view thereof.

The broken lines throughout the drawing figures illustrate portions of the case for electronic communications device that form no part of the claimed design.

1 Claim, 8 Drawing Sheets
